CLAIM

We claim the ornamental design for a motor protection relay, as shown and described.

DESCRIPTION

FIG. 1 is a perspective view of a new and ornamental design for a motor protection relay in accordance to the present design;

FIG. 2 is top view of FIG. 1;

FIG. 3 is a bottom view thereof;

FIG. 4 is a front view thereof;

FIG. 5 is a rear view thereof;

FIG. 6 is a right side view thereof;

FIG. 7 is left side view thereof.

FIG. 8 is a perspective view of the bottom of FIG. 1; and, FIG. 9 is a side perspective view of the bottom of FIG. 1. The broken lines in the drawing are for the purpose of illustrating portions of the article that form no part of the claimed design.
